Primary Examiner — Joseph Kukella*Assistant Examiner* — Heather Wenc(74) *Attorney, Agent, or Firm* — K&L Gates LLP; Brian J. Novak; Giorgios N. Kefallinos(57) **CLAIM**

The ornamental design for an electronic tag holder as shown and described.

DESCRIPTION

FIG. 1 is a front perspective view of an electronic tag holder of my design.

FIG. 2 is a rear perspective view of the electronic tag holder of FIG. 1.

FIG. 3 is a front view of the electronic tag holder of FIG. 1.

FIG. 4 is a rear view of the electronic tag holder of FIG. 1.

FIG. 5 is a first side view of the electronic tag holder of FIG. 1.

FIG. 6 is a second side view of the electronic tag holder of FIG. 1.

FIG. 7 is a top view of the electronic tag holder of FIG. 1; and,

FIG. 8 is a bottom view of the electronic tag holder of FIG. 1.

The broken lines shown in the figures are included for the purposes of illustrating portions of the electronic tag holder and form no part of the claimed design. Randomly dashed lines represent surface shading.
